UNITED STATES PATENT OFFICE.

EDWIN BALL STIMPSON, OF BROOKLYN, NEW YORK.

COMBINED PUNCH AND SETTING-MACHINE.

1,079,376.

Specification of Letters Patent.

Patented Nov. 25, 1913.

Application filed November 7, 1911. Serial No. 658,984

To all whom it may concern:

Be it known that I, EDWIN BALL STIMPSON, a citizen of the United States, residing at Brooklyn, in the county of Kings and State of New York, have invented certain new and useful Improvements in Combined Punches and Setting-Machines, of which the following is a specification.

This invention relates to combined punching and setting machines and has special reference to a machine for punching holes in leather or the like and automatically setting eyelets or other fastening devices in the punched out holes.

The principal object of the invention is to improve and simplify the general construction of devices of this character.

With the above and other objects in view, the invention consists in general, of certain novel features of construction and combinations of parts hereinafter fully described, illustrated in the accompanying drawings, and specifically claimed.

In these drawings, Figure 1 is a front elevation of the machine with the bottom portion of the pillar broken off; Fig. 2 is a vertical longitudinal section on the line 2—2 in Fig. 1 looking in the direction of the arrows; Fig. 3 is a side elevation of the machine looked at from the reverse side of Fig. 2; Fig. 4 is a horizontal section partly in plan on the line 4—4 in Fig. 2; Fig. 5 is a vertical section on an enlarged scale on the line 5—5 in Fig. 4 looking in the direction of the arrows; Figs. 6 and 7 respectively are horizontal sections on the lines 6—6 and 7—7 in Fig. 2; Fig. 8 is a perspective view on an enlarged scale of the plumb-gears and of the punch and eyeletting spindle which they support; Fig. 9 is an enlarged detail view of the eyeletting spindle and the lower portion of the upper set in Fig. 2.

I will now describe the devices of the drawings, reserving it to the claims to point out the novel features and to define the scope of the invention, it being understood that the claims will be given the due range of equivalents to which they may be entitled in view of the art.

The frame of the machine comprises a pillar 1, a bifurcated head with horizontally extending arms 2 and 3, the casting for said head consisting of two vertical sides 4 and 5 (Figs. 1 and 2) joined by an integral web 6 shown in vertical section in Fig. 2.

7 is a vertically reciprocating eyeletting spindle which picks the eyelets from the end of a roadway 8 that delivers the eyelets from the magazine 9, said magazine and roadway pivoting about the pin 10.

11 is a vertically reciprocating punch in back of but independent of the eyeletting spindle 7.

12 is a die mounted in alinement with the punch and in the end of the arm 2 (Fig. 2).

13 is a work-supporting table which reciprocates horizontally in fore and aft direction looking at the front of the machine as in Fig. 2, or reciprocates from left to right, and vice versa, in Fig. 2. This table rolls on ball bearings 14 running in sockets 15 in the tops of the vertical arms of a fork 16 bolted at 17 to the front of the pillar 1. The table 13 is prevented from lifting off the arms 16 as it slides thereon by screws 18, two on a side, the heads of the two front screws being covered by plates 19 to prevent the operator's fingers from getting caught in the slots 20 in the table which, it will be noted, slides relatively to the screws 18 which are fixed. These slots 20 consist of a widened upper portion *a* (Figs. 4 and 5) slidably receiving the heads *c* of the screws; and further consists of narrow portions *b* slidably receiving the unthreaded shank portions *d* of the screws. The above described protective or cover plates are themselves located in recesses in the top of the table 13 to be flush therewith and are secured in that position by screws 21 (Figs. 4 and 5).

The eyeletting spindle 7 is telescopically supported in a cylindrical recess in the upper set 22 (Figs. 2 and 9) and has a head 7^a engaging the top of the contracted lower portion of said recess to prevent the spindle from dropping therefrom.

23 is a spiral spring in the upper portion of the recess bearing on the head of the spindle, to keep the end of the latter yieldingly projected from the bottom of the set 22. However, the novel feature of this portion of the machine is the reduced portion 7^b on the end of the spindle 7 separated by the shoulder 7^c from the upper portion of the spindle. The tendency is for the lint and particles from the material wherein the eyelets are set, to work up into the space between the inside of the socket in the set 22 and the spindle 7, and thereby to make the spindle stick in its socket. This happens even when the spindle tapers to its

extremity,—but in my improvement the shoulder ^{7b} as it slides in the socket keeps it clean and clear. The upper end of the set 22 is fixed in a socket in the bottom of the 5 plunger 24 (Figs. 1, 2, 7 and 8), Fig. 8 showing the plunger and related parts in perspective detached from the machine. The plunger reciprocates vertically in suitable guides G (Figs. 2 and 6) supported 10 on the sides 4 and 5 on the upper arm 3 of the head of the machine, the inner faces of said sides themselves likewise acting as guides for the sides of the plunger. The plunger has a bifurcated upper end 24^a 15 across which a pin 25 (Fig. 2) extends that pivotally connects the lower toggle arm 26 to the plunger. The free end of the upper toggle arm 27 is connected with a trunnion pin 28 (Figs. 1 and 2) supported across the 20 space between the sides 4 and 5 of the upper arm 3 of the machine head.

29 is the connecting rod which operates the toggle arms, said rod at its other end being connected with the crank pin 30 on 25 a cam disk 31 that rotates with the drive shaft 32 and drive pulley 33. This completes the description of the mechanism for reciprocating the eyeleting spindle.

I will next describe the means for reciprocating the punch 11 which is fixed in the 30 lower end of a plunger 34 (Figs. 2 and 8). This plunger 34 slides vertically between the sides of a recess 24^b (Figs. 8, 6, 7 and 2) in plunger 24.

35 35 (Fig. 2) is an elbow lever pivotally supported on a pin 36 extending across between the sides 4 and 5 of the upper arm of the machine head. This lever has a horizontal arm whose rounded end extends into a 40 socket in the upper end of plunger 34 and whose upright arm is normally drawn back to cause the elbow lever to lift the punch by a spring 37 (Figs. 2 and 3) attached to one side 4 of the upper arm of the machine head.

38 is a connecting rod between the upright arm of this elbow lever 35 and the depending arm of another elbow lever 39 (Figs. 2 and 3) pivotally supported on a pin 40 extending 50 across between the sides 4 and 5 of the upper arm of the machine head at the rear thereof. The upper or horizontal arm (shown in Fig. 3) of this last named elbow lever 39 has a horizontal stud 39^a supporting 55 a roller 41 which bears peripherally on the cam disk 42 which is circular except for the single sharp projection shown, and is kept thus bearing against said cam by the spring 37. The diameter of the circular portion 60 of the cam disk 42 is such that it permits the spring 37 to keep the punch plunger 34 raised for nearly a complete rotation of the cam disk and until its projection is reached, whereupon through the described elbow lever 39 and its connections with the punch

plunger 34, it is quickly forced down to punch the hole in the article and is as quickly lifted by the spring 37 after the projection on the cam disk has ridden past the roller 41 (Fig. 3).

I will now describe the means for reciprocating the work-supporting table 13:—46 is a bell crank lever pivoting on a stationary pin 47 (Figs. 2 and 3) and having the end of its vertically depending arm connected with the rear of the table 13 by a link 48 and having the end of its horizontal arm connected by a vertical link 49 (Figs. 2 and 3) with the lever 45 (Fig. 2) whose other end is pivotally supported on the pin 40.

50 is a roller on a horizontal stud supported on the upper side of this lever 45 to bear peripherally on a cam disk 44 which is fixed alongside the other cam disk 42 on the same drive shaft 32. This cam disk 44 (Fig. 2) has a circular portion and a portion of reduced radius leading to said circular portion of greater radius.

51 is a tension spring connecting the horizontal arm of the bell crank lever 46 with a pin projecting from a part of the machine head above said arm, said spring thereby normally holding the table 13 drawn back into its rearmost position with the roller 50 in contact with its cam disk. This is the position of the table as long as the roller 50 is in contact with the portion of the cam having the reduced radius which is nearly one-half the diameter of the cam disk; but as soon as the larger portion of the disk rides around into contact with the roller, its greater radius forces down the lever 45 and through the described connections pushes the table 13 into its forward position and holds it there for somewhat over one-half the given 100 rotation of the cam disk 44.

It will be noted how the above described operating means for the table, punch and eyeleting spindle respectively constitute means for operating said parts in timed relation because the cam disks 44 and 42 and the crank pin 30 controlling the operation of these parts are all carried around together in definite relation to one another. Thus, referring to Fig. 2, the projection of the cam disk 42 is just about to ride past the roller 50 to operate the punch 11. At this time it will be seen that the small radius of the other cam disk 44 is riding on its roller 41 and continues so to do after the punch 11 has completed its stroke and is in up position clear of the article,—which means that during this time the table 13 is maintained at rest, as it should be, to permit the punching operation to take place. As the cam disks continue on their rotation, the larger radius of the disk 44 is soon reached and the table 13 is pushed forward a distance calculated to be exactly equal to the distance between the punch and the eyeleting spindle, with the 120 125 130

result that the punched hole in the article is brought directly under the eyeleting spindle 7 and is kept there for the interval that the larger radius of the cam 44 keeps the lever 45 depressed (Fig. 2). Meanwhile, the crank pin 30 is rotating with the cam disks toward its forward position directly across from its shown position in Fig. 2, and is moving the eyeleting spindle 7 downwardly to enter the eyelet held in the end of the roadway 8, then to pick said eyelet out of the roadway by reason of the roller 53 on the plunger 24 forcing the roadway to the right in Fig. 1 by bearing against the cam face 54 on the roadway, and finally to carry the eyelet on the spindle 7 down through the punched-out hole in the article and to clench it therein by the bottom of the upper set 22 forcing the body of the eyelet against the lower set 55 (Fig. 2) to spread and clench it, the spindle 7 meantime telescoping upwardly into its socket in the upper set. This eyelet, or other form of fastener, setting stroke of the machine is completed when the crank pin 30 is in its above assumed right-hand position in Fig. 2. As it rotates back to its shown left-hand position in that figure, it initiates and completes the up stroke of the eyeleting means.

30 It may here be noted in passing that when the plunger 24 on its down stroke cams back the roadway 8 (Fig. 1) as above described,—the latch 56 drawn down by the spring 57 locks the roadway in cammed back position 35 by the notch in the end of the latch engaging the pin 57^a in the roadway. The latch is raised near the end of the up stroke of the plunger 24 by the pin 58 (Fig. 1) on the plunger contacting therewith, whereupon 40 the tension spring 59 returns the roadway to its normal position shown in Fig. 1 preparatory to feeding an eyelet to the eyeleting means on its next down stroke. Meanwhile, by the described up stroke of the eyeleting means the smaller radius of the cam disk 44 has again reached the roller 50 and has permitted the table 13 to be drawn back preparatory to the next down stroke of the punch.

45 50 To adapt the machine for accurately positioning the eyelets in a lot of calendars or other articles of uniform shape, I have devised a work-positioning gage 60 (Fig. 4) which preferably extends transversely across the table 13 as shown in that figure.

55 61 and 62 designate set screw and slot connections between the gage and the table permitting the former to be fixed in a range of fore and aft positions on the table.

60 63 is an arm projecting forwardly at right angles from the gage and having a set screw 64 and slot 65 connection therewith permitting the arm to be adjusted bodily along the gage. The articles to be punched and 65 eyeleted are positioned one at a time on the

table by fitting the given corner of each in the angle formed between the front edge of the gage 60 and the side of the arm 63, these latter being adjustable relative to each other and the gage being adjustable in position on the table 13 to position the eyelet at exactly the desired location in the article.

70 The front portion of the gage 60 is cut away at 60^a so that it will not strike the presser foot or stripper 66 (Fig. 2) secured to the depending portion of the machine head. It may be noted in passing that, of course, the gage 60 is shown in Fig. 4 as having a position which is too far forward for any working position which it will ever receive, because in the position there shown the article would not be punched at all because the punch is in vertical alinement over the die and the gage will be seen to prevent the article from being under the punch.

75 It is unnecessary to describe the details of the magazine 9, its relation to the roadway, its suspension from the axis 10, and the mechanism by which it is operated from the oscillating arm 70 on the end of the trunnion pin 28 of the upper toggle arm 27, because these parts are substantially the same as those set forth and described in my co-pending application for improvements in setting machines, Serial No. 640,499.

80 71 (Fig. 2) is a rod connected below with the treadle of the machine, which latter, however, is not shown. Above, this rod connects with a well known form of clutch mechanism whereby the drive pulley 33 merely turns idly without rotating the cam disks to operate the machine, so long as the treadle is not operated.

85 72 The particular machine shown in the drawings is a combined punching and eyeleting machine but of course other forms of fastener setting means may be substituted for the eyeleting means, such as means for setting rivets, etc.

90 Having thus described my invention, what I claim is:

95 1. In a combined hole-punching and setting machine, the combination of vertically reciprocating punch means, vertically reciprocating setting means, a horizontally reciprocating work-support which carries the work from the punch means to the setting means so that the holes punched by the punch means are in alinement with the setting means, a crank and means for operating all of the aforesaid means in timed relation, wherein the work-support is moved to the setting means after the punch means has been operated and before the setting means is operated, said means for operating the parts in timed relation comprising a toggle operated by said crank and operatively connected with the setting means, a cam carried around with said crank, cam-lever means 100

coöperating with the cam and itself being operatively connected with the setting means, a second cam carried around with said crank, and cam-lever means coöperating with said second cam and being operatively connected with the work-support.

2. In a combined hole-punching and setting machine, the combination of setting means comprising a suitably guided vertically reciprocating plunger carrying a setting spindle, punch means comprising another vertically reciprocating plunger guided to reciprocate in a recess in the first named plunger, a horizontally reciprocating work-support which carries the work from

the punch means to the setting means so that the holes punched by the punch means are in alinement with the spindle of the setting means, and means for operating all of the aforesaid means in timed relation, wherein 20 the work-support is moved to the setting means after the punch means has been operated and before the setting means is operated.

In testimony whereof I affix my signature 25 in presence of two witnesses.

EDWIN BALL STIMPSON.
